C. E. GOODWIN:
SINGLE TRIGGER DOUBLE BARREL GUN.

(Application filed July 11, 1900.)

(No Model.)

UNITED STATES PATENT OFFICE.

CHARLES EDWARD GOODWIN, OF GENEVA, OHIO.

SINGLE-TRIGGER DOUBLE-BARREL GUN.

SPECIFICATION forming part of Letters Patent No. 665,634, dated January 8, 1901.

Application filed July 11, 1900. Serial No. 23,202. (No model.)

To all whom it may concern.

Be it known that I, CHARLES EDWARD GOODWIN, a citizen of the United States of America, and a resident of Geneva, county 5 of Ashtabula, and State of Ohio, have invented certain new and useful Improvements in Double-Barrel Shotguns, of which the following is a specification.

This invention relates to double-barrel shot-guns, and has for its object to provide such guns with but one trigger, whereby either barrel may be discharged independently or each barrel may be discharged one after the other in rapid succession with the use of the one 15 trigger, the arrangement being such that the trigger mechanism is automatically shifted for the discharge of the barrels in succession.

The nature of the construction and operations of this invention will fully appear from 20 the subjoined description, when considered in connection with the accompanying drawings, in which—

Figure 1 is a side elevation of a portion of a gun-stock having one lock removed and a 25 portion of the central part of the stock broken away to show the relative position of my invention and its adaptation for co-operation with the hammers of the locks. Fig. 2 is a perspective view of my new single-trigger mechanism, together with the lock, showing 30 its adaptation for lifting the sear and the relative position of the safety guide-pin in connection therewith. Fig. 3 is a vertical section through the gun-stock, the locks, and the 35 trigger-plate on line 3 3 on Fig. 2 looking in direction of arrow 1. Fig. 4 is a like vertical section through the stock on line 4 4 looking in direction of arrow 2. Fig. 5 is a vertical section through the lock-plate, the trigger- 40 supporting block, and the studs on line 5 5, Fig. 1. Fig. 6 is a top or plan view of my new trigger mechanism.

A, Fig. 1, represents a portion of a gun-stock. B is a cavity in its side occupied by 45 one of the gun-locks, and C is the trigger-guard. In the stock from the under side I make a cavity or chamber between the two lock-cavities to receive the operating parts of my new trigger mechanism. D is a recessed or hollow block firmly attached to the trigger-plate E, and F is the trigger occupying a 50 slot in said plate and has a bifurcated upright

arm f, by which it is pivoted at f' in the upper rear corner of said block D. g is a spring fixed in the trigger-plate, with one end bearing against said arm f for holding the trigger in its normal position. H is a rear arm of the trigger occupying the slot in the trigger-plate E. G is a lever occupying the space in the bifurcated arm f and is loosely held in place 60 by the pivot f'. Its rear end rests upon the arm H of the trigger, its forward end extends to the front line of the block D, and its upper corner is cut away, so as to pass under the screw-tapped cross-piece of the block D. 65 (Seen at D in drawings.) The rear end of the lever G is made to shift from side to side on the pivot for the purpose of changing its position from under one sear to the other of the locks, respectively, by means as follows: I and J 70 are hollow studs fixed in the sides of the block D, in which are provided telescoping pins i j, the inner heads of which bear, respectively, against the sides of the forward part of the said lever G. The studs extend laterally 75 through the side walls of the middle cavity into the side cavities, so that the outer heads of said pins i j bear, respectively, against the tumblers k of the hammers. The pins i j inside the studs are surrounded by spiral 80 springs s s, (seen in Fig. 6,) which bear against the pin-heads to force them outwardly and inwardly, respectively. The tension of one of the springs is greater than the other, the purpose of which is to hold the tail of the lever G to one side, as seen in Fig. 3, under the sear of the lock at one side of the gun. The operation of this device is as follows: When both locks of the gun are cocked, the pins i j 85 are contacted, respectively, with the tumblers k, the spring on one pin being stronger than the other. The tail of the lever G is still held to one side, as seen at H, in drawings. Now when the trigger is pulled the tail of the lever G is raised by the arm H of the trigger and 90 the sear of the lock on that side of the gun is lifted and the barrel discharged. This also releases the pressure of the tumbler of that hammer on the pin i. Then the pressure of the spring on the opposite pin j, which is 95 greater than that on the pin i, forces the head of lever G over and shifts the tail of said lever over to the right. This brings the tail of the lever under the sear of the opposite ham-

mer. Now by again pulling on the trigger the other barrel is discharged, and thus the two barrels are discharged in rapid succession by two pulls on the one trigger. This description pertains to discharging the left-hand barrel first. In order to reverse this order to discharge the right-hand barrel first, I provide as follows:

P is a push-pin fixed in a hole in the guard and trigger-plate, which is to be pushed up for its upper end to pass between the front end of the lever G and the side of the block D. This will hold the tail of the lever over to the right and under the sear of the hammer on the right side of the gun. A spring V is fixed on the trigger-plate, one end of which will bear against the pin when up to hold it in place. Now when the trigger is pulled the right-hand barrel is discharged first. The push-pin is pushed down by the movement of the lever and the spring-pin i will force the front end of the lever over to the right and bring the tail under the sear of the other hammer. Then by the second pull on the trigger the barrel on the left is discharged.

T is a safety guide-pin fixed in the stock, with its lower end reaching down between the ends of the two sears. (Seen in Figs. 2 and 4.) The end of lever G shifts under this pin and the sears. This pin serves to guide the upward movement of the lever and prevent its contacting with both sears at the same time.

W is a weight pivotally attached to the lever G, with its lower end resting upon the trigger-plate. Its purpose is to hold the lever steady and prevent jarring by the recoil of the gun.

Having described my invention, what I claim is—

1. In a double-barrel shotgun provided with two locks and but one trigger, a rear arm H on said trigger, a block supported on the trigger-plate and having the trigger pivotally supported therein, a lever G loosely supported on the trigger-pivot with its rear end lying on the rear arm H of the trigger, hollow studs I J attached to the sides, respectively, of said

block, and extending laterally through to the lock-chambers, spring-actuated pins i j contained in said studs and contacting, respectively, with the tumblers k k of the two locks, the spring in one stud having greater tension than the other, whereby said lever is made shiftable, substantially as and for the purpose set forth.

2. The combination, in a double-barrel shotgun, having two locks and but one trigger, a rear arm H on said trigger, of the block D mounted on the trigger-plate, and having the trigger pivotally supported thereby, the lever G loosely supported on the trigger-pivot, with its rear end lying on the rear arm H of the trigger, the hollow studs I J attached to the sides, respectively, of said block, and extending laterally through to the lock-chambers, spring-actuated pins i j contained in said studs, and contacting, respectively, with the tumblers k k of the two locks, and the safety guide-pin T fixed in the stock, and adapted to guide the lever for discharging the barrels separately, substantially as described.

3. The combination, in a double-barrel shotgun, having two locks and but one trigger, a rear arm H on said trigger, of the block D mounted on the trigger-plate, and having the trigger pivotally supported thereby, the lever G loosely supported on the trigger-pivot, with its rear end lying on the rear arm H of the trigger, the hollow studs I J attached to the sides, respectively, of said block, and extending through to the lock-chambers, spring-actuated pins i j contained in said studs and contacting, respectively, with the tumblers k k of the two locks, the safety guide-pin T fixed in the stock, and the pin P fixed in the trigger-plate and guard, adapted for reversing the firing order of the barrels, substantially as described.

Signed by me at Cleveland, Ohio, this 27th day of June, 1900.

CHARLES EDWARD GOODWIN.
